US00D823079S

(12) **United States Design Patent** (10) **Patent No.:** **US D823,079 S**
(45) **Date of Patent:** **** Jul. 17, 2018**

(54) **PRUNER**

(71) Applicant: **Fiskars Finland Oy Ab**, Helsinki (FI)

(72) Inventor: **Sami Lyytikäinen**, Helsinki (FI)

(73) Assignee: **Fiskars Finland Oy Ab**, Helsinki (FI)

(**) Term: **15 Years**

(21) Appl. No.: **29/608,080**

(22) Filed: **Jun. 19, 2017**

Related U.S. Application Data

(62) Division of application No. 29/576,832, filed on Sep. 7, 2016.

(30) **Foreign Application Priority Data**

Mar. 24, 2016 (EM) 003042167

(51) **LOC (11) Cl.** **08-01**

(52) **U.S. Cl.**

USPC **D8/4**

(57) **CLAIM**

I claim the ornamental design for a pruner, as shown and described.

DESCRIPTION

The patent or application file contains at least one drawing executed in color. Copies of this patent or patent application publication with color drawing(s) will be provided by the Office upon request and payment of the necessary fee.

FIG. 1 is a front view of the first embodiment of the claimed design;

FIG. 2 is a rear view thereof;

FIG. 3 is a top view thereof;

FIG. 4 is a bottom view thereof;

FIG. 5 is a perspective view thereof;

FIG. 6 is a left side elevation view thereof;

FIG. 7 is a right side elevation view thereof;

FIG. 8 is a front view of the second embodiment of the claimed design;

FIG. 9 is a rear view thereof;

FIG. 10 is a top view thereof;

FIG. 11 is a bottom view thereof;

FIG. 12 is a perspective view thereof;

FIG. 13 is a left side elevation view thereof; and,

FIG. 14 is a right side elevation view thereof.

Any portion of the article depicted in, or bounded by, broken lines forms no part of the claimed design. Broken lines formed by equal length dashes show unclaimed subject matter.

1 Claim, 14 Drawing Sheets
